UNITED STATES PATENT OFFICE.

HENRY FERR, OF MASON CITY, IOWA.

ATTACHMENT FOR OIL-STOVES.

1,389,497.

Specification of Letters Patent. Patented Aug. 30, 1921.

Application filed November 29, 1920. Serial No. 427,082.

To all whom it may concern:

Be it known that I, HENRY FERR, a citizen of the United States, residing at Mason City, in the county of Cerro Gordo and State of Iowa, have invented new and useful Improvements in Attachments for Oil-Stoves, of which the following is a specification.

This invention relates to improvements in stoves and has especial relation to an improvement in oil stoves.

An object of the present invention is the provision of means for utilizing the heat which is thrown off from the burner chimneys of an oil stove, for the purpose of heating water and thus divert to a useful purpose, the heat which is otherwise wasted.

Another object of the invention is the provision of means for carrying out the above object, which may be readily attached 20 to an ordinary oil stove and may be so constructed as to replace the usual burner chimney now in use.

A further object is the provision of an attachment of the above character which is of 25 simple construction and which will permit of ready access to the burners when desired.

With the above and other objects in view, the invention further includes the following 30 novel features and details of construction, to be hereinafter more fully described, illustrated in the accompanying drawings and pointed out in the appended claim.

In the drawings:—

Figure 1 is a front elevation of an oil 35 stove with the improvement applied thereto.

Fig. 2 is a horizontal sectional view of the same.

Fig. 3 is a vertical transverse section.

Fig. 4 is a detail perspective view of the 40 invention removed from the stove.

Referring specifically to the drawings, wherein like characters of reference denote corresponding parts, the invention is shown as comprising a tank 10 which is designed 45 to form a reservoir for water. This tank is preferably rectangular as shown and is provided in its front wall with spaced semi-circular depressions 11, two of such depressions being shown, as the tank illustrated is designed for use in connection with a two burner stove. It is of course obvious that the tank may be constructed for stoves having any number of burners.

Hingedly secured to the front wall of the

tank adjacent one edge of the depression 11 are doors 12, the hinges of these doors being indicated at 13. The doors 12 are substantially semi-circular in cross section and are provided near each edge with laterally extending longitudinal flanges 14, which are adapted to engage within the longitudinal edges of the depressions 11, so that when the doors are closed, the escape of heat along these edges will be prevented. The doors 12 are provided with openings 15, which are 65 preferably covered with mica or other transparent material.

The semi-circular depressions 11 and the doors 12 are designed to provide chimneys for the burner of the stove, the latter being indicated at 16. These burners are of the usual type commonly employed in connection with oil stoves, having an annular flange 17 upon which the usual burner chimney is supported. The present invention is designed to replace these chimneys. The tank 10 is provided at the lower end of each of the semi-circular depressions 11 with an annulus 18, having an inwardly extending flange 19 which is adapted to rest upon the 80 flange 17 of the burners, so that the latter extend upwardly within the space provided by the depressions 11 and the doors 12, the burners being plainly visible through the openings 15 in the ordinary manner. The 85 heat in the burners is thus positioned within the line of the front wall of the tank, so that the latter partially surrounds the burners and the heat from these burners will thus readily heat the contents of the tank.

The top of the tank is provided with a filling opening 20 which is located beneath and closed by the top 21 of the stove. The bottom of the tank is supported along its rear edge by legs 22.

It will be seen from the foregoing description and the accompanying drawings, that the invention provides a novel form of tank which may be substituted for the usual burner chimneys of an ordinary oil stove for 100 the purpose of providing means for utilizing heat from these burners to heat water. If desired, a draw-off cock 23 may be provided for the purpose of removing the water from the tank or reservoir.

The invention is susceptible of various changes in its form, proportions and minor details of construction and the right is here-

in reserved to make such changes as properly fall within the scope of the appended claim.

Having described the invention what is claimed is:—

The combination with a stove including a plurality of burners, of an annulus surrounding the upper end of said burners, a rectangular tank carried by said stove and 10 provided with a plurality of semi-circular

depressions, oppositely curved doors and forming flues therewith and hingedly secured to one edge of each depression, engaging said annulus and provided with a plurality of openings, laterally extending longitudinally of openings, laterally extending longitudinally flanges formed integrally with the outer edge of said doors and means for retaining said doors in closed position.

In testimony whereof I affix my signature.

HENRY FERR.
